US0D1098179S

(12) **United States Design Patent**
Martinez Galan

(10) Patent No.: **US D1,098,179 S**
(45) Date of Patent: ** Oct. 14, 2025

(54) **DISPLAY SCREEN OR PORTION THEREOF
HAVING A GRAPHICAL USER INTERFACE**

(71) Applicant: **Stryker Corporation**, Kalamazoo, MI (US)

(72) Inventor: **Jose Daniel Martinez Galan**, Seattle, WA (US)

(73) Assignee: **Stryker Corporation**, Portage, MI (US)

(**) Term: **15 Years**

(21) Appl. No.: **29/944,450**

(22) Filed: **May 28, 2024**

Related U.S. Application Data

(62) Division of application No. 29/872,350, filed on Mar. 10, 2023, now Pat. No. Des. 1,036,485, which is a division of application No. 29/756,842, filed on Oct. 30, 2020, now Pat. No. Des. 1,012,959.

CLAIM

The ornamental design for a display screen or portion thereof having a graphical user interface, as shown and described.

DESCRIPTION

The patent or application file contains at least one drawing executed in color. Copies of this patent or patent application publication with color drawings(s) will be provided by the Office upon request and payment of the necessary fee.

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

The FIGURE is a front view of a display screen or portion thereof having a graphical user interface.

The dot-dashed broken lines depict the display screen or portion thereof and form no part of the claimed design.

The remaining broken lines showing portions of the graphical user interface form no part of the claimed design.
